UNITED STATES PATENT OFFICE.

FAGGIO MARTINO, OF PERRIS, CALIFORNIA.

SHOE BOTTOM.

Application filed December 16, 1925. Serial No. 75,696.

This invention is designed mainly for use on shoes having leather soles when it is desired to apply to the shoe, both a sole and a heel of rubber; and it may likewise be developed separately and either a sole or heel used; the main feature of my invention being the reinforcing of the rubber by imbedding in said rubber two or more thicknesses of quilted canvas previously stitched together.

An object of my invention is to provide a rubber sole and heel greatly increased in strength and durability over the rubber soles and heels already upon the market and which when attached to a shoe will not allow the heads of the attaching nails to pull through.

Another object is to firmly join a rubber sole and heel in such manner that they will not crack or break at the joining.

Another object is to provide a novel rubber sole, or combined sole and heel which when applied to a shoe will not tend to make the wearer's feet hot as is common with present day rubber soles.

A further object is to provide a rubber sole which when attached will not buckle.

A still further object is to provide a novel rubber sole or combined sole and heel which may be satisfactorily secured to the shoe bottom by nailing.

Other objects, advantages and features of invention may appear from the accompanying drawing, the subjoined detailed description and the appended claims.

The accompanying drawing illustrates the invention in two of the forms in which it may be employed.

Figure 1 is a longitudinal section indicated at line α^1 , Fig. 2, showing a combination rubber sole and heel.

Fig. 2 is a view on a smaller scale of the underside of the canvas reinforcing before the rubber has been applied showing the manner of stitching together the layers of canvas and of attaching the auxiliary heel piece.

Fig. 3 is a like view of a separate sole reinforcement.

Fig. 4 is a longitudinal section on somewhat larger scale of the completed sole, the line of section being at α^1 , Fig. 3.

Fig. 5 is a section analogous to Fig. 1 showing the manner of applying a new heel after the worn heel has been cut off and re-

moved. The greater part of the sole is broken away to contract the view.

The sole reinforcing or interlining 1 is composed preferably of two or more layers of canvas as a , b , c , in Figs. 1 and 2, and a , b , in Figs. 3 and 4. The several layers are joined, stiffened and strengthened by stitching 2. A thin top facing of rubber 3 is cemented onto the canvas 1 to form a smooth surface for the foot and a more or less thick tread of rubber 4 is cemented onto the underside of said canvas.

A heel piece 5 constructed of canvas in similar manner to the piece 1 with stitching 2' is first secured by stitching the same at 6 to the sole reinforcing 1.

A cushion of rubber 7 is then inserted between the heel piece 5 and the sole 1 and secured by nails 8.

The heel piece is narrowed at 9 to allow stitching around the edge of the sole 1 without sewing into the heel 5.

I do not limit myself to the combination of the heel and sole as either may be used separately and as rubber heels applied separately have for years been used, I make no claim for such use, but the use of rubber soles as illustrated in Figs. 3 and 4, I claim as new.

The sole 10 shown in said Figs. 3 and 4 is practically the same as heretofore shown and described in Figs. 1 and 2 with the exception that the heel is omitted; the edge 11 of the sole 10 being beveled to present a smoother edge as is common with leather soles.

To replace a worn rubber heel at 12 with a new heel, the heel 12 may be cut off at 13 as shown in Fig. 5 and a heel 12' of the construction shown in a former application of mine, Serial No. 2543, filed January 15, 1925, allowed September 16, 1925, may be applied and attached by the nails 8' to the heel foundation which comprises the heel piece 5, the rubber cushion 7 and the canvas reinforcing member 1.

The sole and heel reinforcing members 1 and 5 are preferably more closely joined by the nails 14 which are clinched on said pieces after the cushion 7 has been inserted therebetween.

I claim:

1. A combined sole and heel comprising a rubber tread and a facing, an intervening reinforcement of canvas, an auxiliary heel

piece of canvas attached to said reinforcement, attached to said reinforcement, attached to said reinforcement, and an intervening cushion of rubber between said reinforcement and heel piece.

5. 2. A combined sole and heel comprising a rubber tread and a facing, an intervening reinforcement comprising two or more thicknesses of canvas stitched together, an auxiliary heel piece of like composition to the

In testimony whereof, I have hereunto set my hand at Los Angeles, California, this 15
7th day of December, 1925.

FAGGIO MARTINO.
